UNITED STATES PATENT OFFICE

JOSEPH SACHS, OF WEST HARTFORD, CONNECTICUT

ELECTRIC-CIRCUIT-CONTROLLING APPLIANCE

Application filed March 9, 1927. Serial No. 173,979.

The invention relates to a circuit controlling appliance comprising a base spaced from a rear supporting wall and also comprising a switching device located between the supporting wall and the plane of a rearward facing surface of the base and preferably including a sliding member movable parallelly with the supporting wall and located at least in part behind the said base. The invention is particularly applicable to an appliance of the type described wherein fuse contacts are mounted on the base, at least one of them being connected with a corresponding contact of the switching device. A construction embodying the present invention is similar in some respects to that disclosed in my copending application for electric circuit controlling appliance, Serial No. 153,966 filed December 10, 1926, and it is similar in other respects to that disclosed in my copending application for electric circuit controlling appliance, Serial No. 165,645, filed February 3, 1927. An appliance embodying the invention set forth in application Serial No. 153,966 has the fuse contacts arranged at the front of the base and it has the switch contacts arranged preferably at the back thereof and directly carried thereby. An appliance embodying the invention set forth in application Serial No. 165,645 has the fuse contacts at the front of the base and it has the switch contacts preferably at the rear of the base, but so connected with the rear supporting wall that the base with the fuse contacts thereon can be removed, leaving the switch contacts undisturbed and supported on the said wall.

The general object of the present invention is to provide a fused switch having certain features of the fused switches disclosed in the said applications, but having the said features combined to produce new and advantageous results. An appliance embodying the present invention has some of the switch contacts carried directly by the base as in application, Serial No. 153,966 and it has the other switch contacts supported on the rear supporting wall as in application, Serial No. 165,645.

When, as preferred, the switch comprises four separate switch contacts with a slidable

switching member associated therewith, the two switch contacts which are electrically connectible respectively with the fuse contacts are carried by the fuse base to be removable therewith and the switch contacts which are connectible with the circuit wires are carried by the rear support so as to remain in fixed positions when the fuse base is removed. It will be observed that with this arrangement there is the advantage that detachable electrical connections are minimized, the base being removable to provide access to the switch without detaching any wires. In the construction shown in application Serial No. 153,966, the circuit wires had to be disconnected from their terminals in order to permit the entire appliance, including the switch, to be removed; and in the construction shown in application Serial No. 165,645, the electrical connections between the fuse contacts and the corresponding switch contacts have to be broken in order to permit the base with the fuse contacts to be removed. This breaking of electrical connections is entirely avoided in the present construction as the switch contacts connected with the fuse contacts remain so connected and are removed, and the switch contacts connected with the wires remain so connected and are not removed.

A further advantage of an appliance embodying the invention is that the switch contacts are more readily accessible for cleaning or adjustment. Obviously the contacts carried by the base are entirely exposed when the base is removed and the removal of the said contacts provides additional space facilitating the cleaning or adjustment of the remaining contacts.

Other and more specific objects of the invention will be apparent from the following specifications and claims.

In the accompanying drawings, I have shown one embodiment of the invention, together with certain possible variations thereof, but it will be understood that the drawings are intended for illustrative purposes only and are not to be construed as defining or limiting the scope of the invention, the claims forming a part of this specification.

being relied upon for that purpose. It will be particularly understood that the construction may be varied by substituting therein the alternate details of construction which are fully shown in the copending applications already referred to.

Of the drawings:

Figure 1 is a fragmentary front view of a fused switch embodying the invention, one-half of the fuse block together with the corresponding fuse contacts being omitted in order that the switch construction may be more clearly shown.

Fig. 2 is a bottom view of the parts shown in Fig. 1, the enclosing cabinet being shown in section.

Fig. 3 is a sectional view taken along the line 3—3 of Fig. 1.

Fig. 4 is a fragmentary sectional view similar to Fig. 3, but showing an alternate means of connection between the fuse block and the supporting elements therefor.

Fig. 5 is a perspective view illustrating the removability of the base and associated parts and also of the movable element of the switch.

Fig. 6 is a fragmentary view similar to Fig. 1, but showing an alternate supporting means for the fuse block.

Fig. 7 is a fragmentary sectional view taken along the lines 7—7 of Fig. 6.

As shown in the drawings, there are two pairs of fuse contacts and two separate switching devices, but it will be understood that the invention is not limited to any particular number of fuses and switches. The fuse and switch contacts are shown as symmetrically disposed with respect to the vertical central plane of the appliance and for the sake of convenience and simplicity of description, I will describe in detail only those parts at one side of the said plane, it being understood that the parts on the other side are, or may be, the same in construction except for reversal of positions.

As shown in the drawings, there is a base 1 which is supported in fixed spaced relation with a rear support. When there is an enclosing cabinet, this support may be the rear wall of the cabinet. Preferably fuse contacts such as 2 and 3 are provided, these being mounted on the base 1 at the front thereof. These fuse contacts are shown as adapted for receiving a cartridge enclosed fuse F, but it will be understood that the invention is not limited for use with fuses of this particular type.

In addition to the main rear support, which as stated may be the rear wall of the cabinet, I prefer to also provide an independent insulating supporting device which is ordinarily secured to the main rear support but which is nevertheless separate therefrom. This supporting device is shown at 4 in the drawings and it may comprise a single block, bar or plate of insulating material.

Suitable means are provided for normally holding the base in the aforesaid fixed spaced relation with the rear support. Preferably, this means is in the form of a plurality of supporting elements which are connected at their forward portions with the base and at their rear portions with the main rear support, preferably indirectly by means of the separate supporting device 4. The elements therefore serve to support the base in the described relationship with the said rear support. These same elements may also serve to support the fixed or non-removable switch contacts, but as to this feature I do not necessarily limit myself.

As shown in Figs. 1 to 3, there are four such supporting elements represented respectively at 5, 5 and 6, 6, these having their front portions connected directly with the base by means of connecting elements 7, 7 and having their rear portions connected with the supporting device 4 by means of screws 8, 8. The supporting elements 5, 5 and 6, 6 are shown as being U-shaped, but as to this there may be wide variation. In this way the fuse contacts and the supporting device are held in fixed spaced relationship with each other, these parts together with the supporting elements and other associated parts constituting a unit which can, if desired, be secured to or removed from the rear support without disturbing their assembled relationship.

Located in the space behind a vertical plane extending through the rear parts of the base 1 is a switching device. As concerns the broader phase of the invention, the type of switching device may be varied, but preferably the switching device comprises two or more normally stationary switch contacts and a switching element which is rectilinearly movable substantially parallelly with the aforesaid vertical plane and with the front face of the support.

As concerns some of the broader phases of the invention, the location and mounting of the stationary switch contacts can be varied, but, preferably and in accordance with other phases of the invention, at least one of the said switch contacts is mounted directly upon and electrically connected with one of the supporting elements 5 or 6. Preferably and as shown, two switch contacts 9 and 10 at each side are mounted upon and electrically connected with the corresponding supporting elements 5 and 6. The contacts are preferably of a resilient generally U-shaped form as shown. Connected with the supporting elements 5 and 6 and thus connected with the switch contacts 9 and 10 are wire connecting terminals 11 and 12 each adapted for the connection of either an incoming circuit wire or an outgoing circuit wire. I have shown terminals of the solder lug type but I do not so limit myself.

Each of the switch contacts 9 and 10 is preferably one of a pair. The other contacts of the pairs are shown at 13 and 14 respectively and they are similar respectively to the contacts 9 and 10, but are oppositely positioned. Contact supporting elements 15 and 16 are provided for the contacts 13 and 14, these being carried solely upon the base 1 at the rear thereof and being electrically connected respectively with the fuse contacts 2 and 3. As shown, each of the said supporting elements is held in place by means of a screw 17. The screw 17 may also serve as a means of electrical connection between the corresponding fuse and switch contact, but other connecting means may be employed if desired.

For establishing or breaking electrical connection between the switch contacts of the said pairs 9, 13 and 10, 14, I provide for each pair a switching element which is rectilinearly movable substantially parallelly with the front face of the supporting device and with the rear face of the fuse base. When there are two pairs of stationary switch contacts there are two conducting switching elements 18 and 19 insulated from each other and adapted respectively to engage and disengage the said normally stationary switch contacts. The two conducting switching elements 18 and 19 are preferably carried by an insulating element 20, which with the said conducting elements constitutes a rectilinearly movable switching member. The insulating element 20 is preferably in the form of a flat plate, the said conducting elements 18 and 19 extending through it and projecting somewhat beyond the opposed surfaces thereof as shown. The details of the switching member may be as shown in my said copending application, Serial No. 153,966. When the stationary switch contacts are located as shown, the said flat insulating element 20 is arranged perpendicularly to the supporting device and to the fuse base. The said element may extend into grooves 21 and 22 formed in the said supporting device and in the said fuse base respectively.

From the foregoing description, it will be apparent that when the switching member is in the "on" position, as shown in Fig. 1, a circuit will be established from the wire connecting terminal 11 through the contact supporting element 5 and the switch contacts 9, 18 and 13, to the supporting element 15 and thence to the fuse contact 2. Similarly a connection is established from the fuse contact 3 through the supporting element 16 and the switch contacts 14, 19 and 10 to the contact supporting element 6 and the wire connecting terminal 12. When the switching member is moved upward from the position shown in Fig. 1, the elements 18 and 19 will be disengaged from

the stationary switch contacts and circuit will be broken at two points at each side of the fuse, thus making a total of four breaks. The insulating element 20 of the switching member serves not only as a carrier for the contacts 18 and 19, but it also serves as a barrier which is moved between the opposite stationary contacts immediately upon the disengagement of the corresponding movable contact 18 or 19 therefrom. Although the switching member is guided between the supporting device 4 and the base 1 and is held by these parts against forward or backward movement, it is entirely free to adjust itself laterally to conform to the positions of the several stationary switch contacts. If there are any defects in the initial construction or mounting of these stationary contacts or in the subsequent adjustment thereof, the switching member will conform thereto and will at all times effect firm engagement with the contacts and will establish effective electrical connections therewith.

When there are two switching devices as shown and described, there is preferably provided an insulating baffle plate 23 located between them. This is shown as being held in slots in the supporting device and in the fuse base.

It will be noted that I have shown the stationary switch contacts as located respectively beyond the top and bottom edges of the fuse base, so as to be readily accessible from the front. The supporting elements 5 and 6 extend downward and upward from the fuse base and then extend rearward, and the contact supporting elements 15 and 16 are similarly constructed and located. The location of the said contacts above and below the fuse base leaves them exposed for convenient inspection and cleaning without the necessity for disassembling any parts of the appliance. Recesses 24, 24 may be provided in the edges of the fuse base 1 to facilitate inspection and cleaning. The stationary switch contacts are connected with the corresponding supporting elements by means of screws 25, 25 to permit the contacts to be easily removed for replacement, if necessary.

While I do not herein narrowly limit myself as concerns the locations of the stationary switch contacts in the direction of movement of the movable switching member, it will be observed that the said contacts are nevertheless preferably located behind the plane of a rearward facing surface of the base. It will also be observed that the switching device as a whole is so located that at least a part of the movable member thereof is directly behind the base.

The appliance is preferably enclosed in a cabinet, a part of a suitable cabinet being shown. The cabinet has a rear wall 26, side walls 27, 27 and an openable front cover 28.

The supporting device 4 may be secured to the rear wall 26 by means of screws 29, 29.

The cabinet may be utilized as a means for supporting the switch operating means and as shown, there is an operating spindle 30 including two pivot sections 31 and 32 extending through bearing apertures in the side walls 27, 27 of the cabinet. The said spindle includes a manually operable handle 33 outside of the cabinet and also includes a crank section 34 inside of the cabinet and between the pivot sections. The crank section is operatively connected with the movable switch member.

I provide a suitable operative connecting means between the swinging crank section 34 and each of the rectilinearly movable switching members. Preferably this connecting means is so constructed as to permit the assembly or disassembly of the insulating element with or from the operating means and the cabinet by simply moving the insulating element rearward or forward. For this purpose, I have shown in each insulating element 20 a slot 35 adapted to receive the crank section 34. The slot 35 is preferably open at one end, that is, at the back end, so as to facilitate assembly or disassembly as described. From the foregoing description, it will be obvious that by moving the handle 33 each of the switch members can be moved longitudinally upward or downward, as desired. With the handle 33 in its uppermost position, the switching members will be held in their lowermost positions as shown in Figs. 1 and 3, thus completing the circuit through the appliance. When the handle 33 is moved to its lower position, the switching members will be moved to their upper positions, thus separating the movable contacts 18 and 19 from the stationary contacts 9, 13 and 10, 14 respectively and thus breaking each leg of the circuit at four points as already fully described.

The slot 35 is shown as being near the middle of the insulating element, this location being ordinarily preferable, but it will be understood that I do not herein limit myself to this location. The baffle plate 23 is provided with an opening 23' to provide clearance for the crank section 34 of the operating spindle.

When it is desired to place the crank section 34 of the operating spindle very close to the contacts, the said crank section may be surrounded by insulating material in order to avoid any possible short circuits. This insulating material may vary as to details, but I have shown a round tube 36 which may be longitudinally split along one side in order to permit its assembly along the spindle. It will be understood that the slot 35 is wide enough to receive not only the crank section of the spindle but also the tube 36 on the said section. I do not herein claim the switch

mechanism including a tube or other insulation surrounding the cranked portion of the spindle as this subject matter is set forth and claimed in my copending application for switch operating mechanism, Serial No. 365,420 filed May 23, 1929, as a continuation-in-part of my aforesaid application Serial No. 153,966.

It will be apparent that by opening the cover 28 of the cabinet access can be had to the entire appliance, all of the parts thereof remaining in their normal relationship when the cover is opened. This is in contrast with earlier proposed appliances having parts mounted upon the cover so that access to the appliance could be had only by moving the said parts on the cover out of their normal relationship with the remaining parts.

It is usually preferable to permit access to the fuses and fuse contacts when the main cabinet cover is closed and sealed, and for this purpose the said cover is shown as being provided with an opening 37 through which the said fuses and contacts are accessible. The relationship between the cover and fuse base 1 is such that the base serves to entirely close the said opening when the cover is in closed position. As shown, the cover is flat and is provided with a depressed portion 38 which terminates at the said opening 37 and the base 1 is provided with an extension 39 which surrounds the fuse contacts and fuses and which engages or approximately engages with the cover depression 38 when the cover is in closed position. Preferably, a part of the extension 39 projects through the opening 37 so as to positively prevent the insertion of wires or other conductors through the opening into engagement with live parts within the cabinet.

Preferably there is provided an auxiliary cover for the opening 37 and the parts are so constructed that the fuse cover cannot be opened when the switch handle 33 is in the position corresponding to the closed position of the switch and so that the handle 33 cannot be moved to the position corresponding to the closed position of the switch when the cover is open. I have shown a sidewise opening flat cover 40 for the fuses, this cover preferably directly engaging the main cover 28 for sliding movement thereon. Rigidly secured to the main cover 28 is a sheet metal guide 41 having an opening 42 therein which registers with the opening 37 in the main cover. The guide 41 is spaced from the main cover so that the fuse cover 40 is slidably mounted between the said parts. The said fuse cover 40 is provided with a knob 42' which serves as a means for moving the fuse cover and which also serves as a stop for limiting the movement of the said cover in either direction. Fig. 2 shows the cover 40 in its left hand closed position. It will be observed that when the fuse cover is in closed position and the switch

handle 33 in the switch closing position, the said handle directly obstructs the cover and prevents the opening movement thereof. When the fuse cover is in its open position having been moved to the right from the position shown in Fig. 2, the said cover directly obstructs the handle 33 and prevents its movement to switch closing position. The specific construction and the interrelationship as herein described between a sidewise opening cover and a switch operating handle are not claimed as part of the present invention, these being set forth in my patents for enclosed fused switches, Nos. 1,721,493, 1,721,494 and 1,721,495, all issued July 16, 1929.

The base 1 has been described as connected with the supporting elements therefor these elements as shown in Figs. 1 to 3 being the supporting elements 5, 5 and 6, 6. As concerns some of the broader phases of the invention, the base may be rigidly and permanently connected with these elements, but I prefer to detachably connect it so that it can be removed from its normal position in order to permit free access to the switching device. As shown most clearly in Fig. 3, each of the connecting elements 7 may be in the form of a screw and in this case the base may be disconnected from the supporting elements simply by unscrewing the said screws 7.

In Fig. 4, I have shown a construction similar to that shown in Fig. 3, but differing in that the fuse base is so mounted that it may be readily removed by direct manual action and without the use of tools. Instead of providing means such as the screws 7, 7 for holding the base in place, I have provided frictionally acting resilient devices, of which one is shown at 7^a. Each of these enters an unthreaded hole in the corresponding supporting element 5^a. The element 7^a is in the form of a screw which is held in place by a nut 43, located in a recess 44 in the base. The rear end of the screw 7^a is split as shown at 45 and it normally enters and engages the sides of an unthreaded hole formed in the corresponding supporting element. Thus, the elements 7^a serve to frictionally hold the base in place without, however, forming any positive connection and thus leaving the base free to be manually removed in a forward direction. It may be desirable to avoid the necessity of depending entirely upon the frictional engagement of the elements 7^a with the corresponding supporting elements for holding the base in place. When elements such as 7^a are used, I prefer to provide additional means normally serving to positively hold the fuse block against forward movement. When the cover of the cabinet is constructed and arranged as already fully described, the cover serves as such a means, the relationship between the base and the cover being the same as shown in Fig. 3. The cover serves when closed to positively prevent removal of the

base, but nevertheless when open leaves the fuse block free to be readily removed as described.

Figure 5 illustrates very clearly the removability of the fuse base with its attached parts and also of the slidable switching members. This view shows the base 1 entirely removed from the rear support, the connecting elements 7, 7 or 7^a, 7^a having been withdrawn from the supporting elements 5, 5 and 6, 6. It will be noted that the switch contacts 13, 13 and 14, 14 have been removed with the base, the electrical connection between these contacts and the corresponding fuse contacts 2 and 3 remain intact. The switch contacts 9, 9 and 10, 10 remain in place on the rear support and remain electrically connected with the respectively corresponding circuit wires.

With the base 1 removed, the slidable switching members 20, 20 are no longer supported or held at the front and are therefore free to be withdrawn in the forward direction. It will be understood that these switching members will ordinarily be moved to the "off" position before being withdrawn. An inspection of Fig. 5 shows that when the base with its attached switch contacts is removed and when the movable switch member 20, 20 are removed, all portions of the switch are freely accessible for inspection, cleaning or adjustment.

Fig. 5 also illustrates the fact that when the fuse base with its contacts and also the sliding switching members are removed the remaining parts of the switching appliance can be easily assembled with or removed from the cabinet and the operating spindle. In the initial assembling of the appliance the operating handle is ordinarily put in place in the cabinet before the switching mechanism is put in place. With the base, the sliding switching members and also the baffle plate 23 removed, it is an easy matter to insert the supporting device 4 with the attached parts under the operating spindle, the said supporting device being first introduced in reversed position with the supporting elements 5, 5 or 6, 6 at one end hooked under the spindle. Then the supporting device with the attached parts is turned over and secured in place as shown by means of the screws 29, 29.

I have shown and described supporting elements 5, 5 and 6, 6 for supporting the base, which elements also serve to carry the switch contacts 9 and 10. I do not, however, limit myself to the use of the same supporting elements for supporting both the base and the switch contacts. In Figs. 6 and 7, I have shown separate supporting elements for these purposes.

As shown in these figures there is an independent supporting element 46 for the base 1, it being understood that two such elements would ordinarily be used. Each element 46 comprises a metallic strip bent to the shape

shown and suitably secured to the supporting device 4, as for instance by means of screws 47, 47. Screws 29^b, 29^b are shown for securing the entire appliance to the back wall of the cabinet. The fuse base 1^b is similar to that shown in Figs. 1 to 5, but it is provided at each side with an extension 48 sufficiently wide to engage the corresponding supporting element. This extension is connected with the supporting element by means of screws 49, 49, which may be removed to permit removal of the base.

The switch contacts 9 and 10 are carried by supporting elements 5^b and 6^b which are, or 15 may be, similar to the supporting elements 5 and 6, but which are not extended to engage the base, the base being entirely supported on the elements 46 as already described.

In my aforesaid application, Serial No. 20 165,645, I have shown several features of construction which may obviously be combined with those herein described. These features include interchangeable fuse blocks, a supporting device consisting of two parallel insulating bars instead of a single plate; an operating spindle arranged with its axis close to the rear wall instead of widely separated therefrom; and meter testing devices associated with the fuse switch and carried by 25 the same rear supporting device. For the sake of simplicity, I have avoided showing these several features of construction in the present case, but it will be understood that they may be combined with the constructions 30 herein shown.

What I claim is:

1. In an electric switch, the combination of a rear support, an insulating base mounted at the front of the support and in normally fixed spaced relationship therewith, 40 two stationary switch contacts located behind the plane of a rearward facing surface of the base and having parallel opposite contact faces substantially perpendicular to the said surface, one of the said contacts being mounted upon the rear support independently of the base and the other being mounted directly upon the base, and a rectilinearly movable switching member movable parallelly with the said rearward facing surface of the base and having opposite parallel contact faces which engage and disengage the two stationary contacts to make and break the circuit through the switch.

2. In a fused switch appliance, the combination of a rear support, an insulating base mounted at the front of the support and in normally fixed spaced relationship therewith, a pair of fuse receiving contacts on the base, two stationary switch contacts located behind the plane of a rearward facing surface of the base and having parallel opposite contact faces substantially perpendicular to the said surface, one of the said contacts being mounted upon the rear support inde-

pendently of the base and the other being mounted directly upon the base, and electrically connected with one fuse contact, and a rectilinearly movable switching member comprising an insulating element engaging at its front with the base to be guided thereby and also comprising a conducting element carried by the insulating element and having parallel contact faces which engage and disengage the two stationary contacts to make and break the circuit through the switch.

3. In a fused switch appliance, the combination of a rear support, an insulating base, a pair of fuse receiving contacts mounted on the base, a plurality of elements of conducting material structurally separate from the base and the support but connected therewith for supporting the former in normally fixed spaced relation with the latter, a wire terminal connected with one of the said supporting elements, two stationary switch contacts located behind the plane of a rearward facing surface of the base with one of them mounted directly upon and electrically connected with the said base supporting element having the wire terminal connected therewith and with the other of them mounted directly upon the base independently of the said supporting elements and electrically connected with one fuse contact, a movable switching element normally engaging the said stationary switch contacts to establish a circuit through the appliance, and means for moving the switching element to disengage it from or reengage it with at least one of the stationary switch contacts.

4. In a fused switch appliance, the combination of a rear support, an insulating base, a pair of fuse receiving contacts mounted on the base, a plurality of elements of conducting material normally connected with the base for supporting it in spaced relation with the said rear support, two stationary switch contacts located behind the plane of a rearward facing surface of the base and having parallel opposite contact faces substantially perpendicular to the said rearward facing surface of the base, one of the said contacts being mounted directly upon and electrically connected with one of the last said base supporting elements and the other of them being mounted directly upon the base independently of the said supporting elements and electrically connected with one fuse contact, a rectilinearly movable switching element normally engaging the said stationary switch contacts to establish a circuit through the appliance, and means for rectilinearly moving the switching element approximately parallelly with the rear face of the base to disengage it from or reengage it with both of the stationary contacts.

5. In a fused switch appliance, the combination of a rear support, an insulating base, a pair of fuse receiving contacts mounted

on the base, a plurality of elements normally connected with the base for supporting it in spaced relation with the said support, two pairs of switch contacts located behind the plane of a rearward facing surface of the base with one contact of each pair mounted directly upon a corresponding base supporting element and with the other contact of each pair mounted directly upon the base independently of the said supporting elements and electrically connected with a corresponding fuse contact, a rectilinearly movable switching member comprising two conducting elements insulated from each other and each normally engaging the said switch contacts of the corresponding pairs to establish a circuit through the appliance, and means for rectilinearly moving the switching member approximately parallelly with the rear face of the base to disengage the conducting elements thereof from or re-engage them with all of the switch contacts.

6. In a fused switch appliance, the combination of an insulating rear supporting device, an insulating base mounted at the front of the rear supporting device and in normally fixed spaced relationship therewith, a pair of fuse receiving contacts on the base, two stationary switch contacts located behind the plane of a rearward facing surface of the base and having parallel opposite contact faces substantially perpendicular to the said surface, one of the said contacts being mounted upon the rear support independently of the base and the other being mounted directly upon the base and electrically connected with one fuse contact, and a rectilinearly movable switching member movable parallelly with the said rearward facing surface of the base and having opposite parallel contact faces which engage and disengage the two stationary contacts to make and break the circuit through the switch.

7. In a fused switch appliance, the combination of an insulating base, a pair of fuse receiving contacts mounted on the base, an insulating supporting device spaced rearward from the said base and adapted to be secured to a rear supporting wall, a plurality of supporting elements structurally separate from the base and the supporting device but normally connected therewith for supporting the former in normally fixed spaced relation with the latter, two stationary switch contacts located behind the plane of a rearward facing surface of the base with one of them mounted upon a supporting device and with the other of them mounted directly upon the base independently of the said supporting device and electrically connected with one fuse contact, a rectilinearly movable switching element normally engaging the said stationary switch contacts to establish a circuit through the appliance, and means for rectilinearly moving the switching element ap-

proximately parallelly with the rear face of the base to disengage it from or re-engage it with both of the stationary switch contacts.

8. In an electric switch, the combination of a rear support, an insulating base, means for detachably and removably mounting the base on the support at the front thereof and in normally fixed spaced relationship therewith, two stationary switch contacts located behind the plane of a rearward facing surface of the base and having parallel opposite contact faces substantially perpendicular to the said surface, one of the said contacts being mounted upon the rear support independently of the base and the other being mounted directly upon the base so as to be removable therewith from the rear support, and a rectilinearly movable switching member movable parallelly with the said rearward facing surface of the base and having opposite parallel contact faces which engage and disengage the two stationary contacts to make and break the circuit through the switch.

9. In an enclosed fused switch appliance, the combination of an enclosing cabinet having an openable front cover, an insulating base in the cabinet, a pair of fuse receiving contacts on the base, means independent of the said cover for detachably and removably supporting the base within the cabinet in normally fixed spaced relationship with the rear wall thereof, a stationary switch contact mounted upon the said rear wall, a second normally stationary switch contact mounted directly upon the base and removable therewith from the cabinet, a movable switching element normally engaging the stationary switch contacts to establish a circuit between them, and means for moving the switching element to disengage it from or re-engage it with both of the stationary switch contacts.

10. In an enclosed fused switch appliance, the combination of an enclosing cabinet having an openable front cover, an insulating base in the cabinet, a pair of fuse receiving contacts on the base, a plurality of supporting elements supplemental to the cabinet and to the base and permanently connected with the former, means independent of the cabinet cover for detachably and removably supporting the base upon the said supporting elements in normally fixed relationship with the said rear support, a stationary switch contact mounted upon the rear wall of the cabinet, a second normally stationary switch contact mounted directly upon the base and removable therewith from the cabinet, a movable switching element normally engaging the stationary switch contacts to establish a circuit between them, and means for moving the switching element to disengage it from or re-engage it with both of the stationary switch contacts.

11. In an enclosed fused switch appliance, the combination of an enclosing cabinet having an openable front cover, an insulating base in the cabinet, a pair of fuse receiving contacts on the base, means independent of the said cover for detachably and removably supporting the base within the cabinet in normally fixed spaced relationship the rear wall thereof, a stationary switch contact mounted upon the said rear wall, a second normally stationary switch contact mounted directly upon the base and removable therewith from the cabinet, a rectilinearly movable switching element normally engaging the stationary switch contacts to establish a circuit between them, and means for rectilinearly moving the switching element approximately parallelly with the rear wall of the cabinet to disengage it from or re-engage it with both of the stationary switch contacts. 70
12. In a fused switch appliance, the combination of a rear support, an insulating base, a pair of fuse receiving contacts on the base, a plurality of supporting elements supplemental to the support and to the base and permanently connected with the former, means for detachably and removably supporting the base upon the said supporting elements in normally fixed spaced relationship with the said rear support, two pairs of switch contacts located behind the plane of the rear face of the base with one contact of each pair mounted directly upon a corresponding base supporting element and with the other contact of each pair mounted directly upon the base and removable therewith from the rear support, a rectilinearly movable switching member comprising two conducting elements insulated from each other and each normally engaging the said switch contacts of the corresponding pairs to establish a circuit through the appliance, and means for rectilinearly moving the switching member approximately parallelly with the rear face of the base to disengage the conducting elements thereof from or re-engage them with all of the switch contacts. 80
13. In an electric switch, the combination of a rear support, an insulating base, means for detachably and removably mounting the base on the support at the front thereof and in normally fixed spaced relationship therewith, two stationary switch contacts located behind the plane of a rearward facing surface of the base and having parallel opposite contact faces substantially perpendicular to the said surface, one of the said contacts being mounted upon the rear support independently of the base and the other being mounted directly upon the base, so as to be removable therewith from the rear support, a rectilinearly movable switching member movable parallelly with the said rearward facing surface of the base and having opposite parallel contact faces which engage and disengage the two stationary contacts to make and break the circuit through the switch the said switching member being normally guided at the front by the base, and means for rectilinearly moving the switching member, the said means being arranged to permit the free removal of the switching member in the forward direction when the base is removed. 85
14. In an enclosed fused switch appliance, the combination of an enclosing cabinet having an openable front cover, an insulating base in the cabinet, a pair of fuse receiving contacts on the base, means independent of the said cover for detachably and removably supporting the base within the cabinet in normally fixed spaced relationship with the rear wall thereof, a stationary switch contact mounted upon the said rear wall, a second normally stationary switch contact mounted directly upon the base and removable therewith from the cabinet, a rectilinearly movable switching element normally engaging the stationary switch contacts to establish a circuit between them, means for rectilinearly moving the switching element approximately parallelly with the rear wall of the cabinet to disengage it from or re-engage it with at least one of the switch contacts, and means normally holding the movable switching element against forward movement with respect to the stationary contacts but adapted to permit such forward movement when the base is removed. 90
15. In an enclosed fused switch appliance, the combination of an enclosing cabinet having an openable front cover, an insulating base in the cabinet, a pair of fuse receiving contacts on the base, means independent of the said cover for detachably and removably supporting the base within the cabinet in normally fixed spaced relationship with the rear wall thereof, a stationary switch contact mounted upon the said rear wall, a second normally stationary switch contact mounted directly upon the base and removable therewith from the cabinet, a rectilinearly movable switching member, the said movable member comprising an insulating element and a conducting element carried thereby and normally engaging the stationary switch contacts to establish a circuit between them and the said movable member engaging at its front with the said base and being freely removable from the cabinet and from the last said stationary contact when the base has been removed, and means for rectilinearly moving the switching member approximately parallelly with the rear wall of the cabinet to disengage the conducting element thereof from or re-arrange it with both of the switch contacts the last said means permitting forward removal of the switching member as aforesaid. 100
- JOSEPH SACHS. 139

CERTIFICATE OF CORRECTION.

Patent No. 1,755,366.

April 22, 1930.

JOSEPH SACHS.

It is hereby certified that error appears in the printed specification of the above numbered patent requiring correction as follows: Page 2, line 102, for "phase" read phases; and page 8, line 125, claim 15, for "re-arrange" read re-engage; and that the said Letters Patent should be read with these corrections therein that the same may conform to the record of the case in the Patent Office.

Signed and sealed this 15th day of January, A. D. 1935.

Leslie Frazer

(Seal)

Acting Commissioner of Patents.
